CLAIM

The ornamental design for a star shaped knob, as shown and described.

DESCRIPTION

FIG. 1 is a perspective of a star shaped knob showing a screw turned by the knob in phantom;

FIG. 2 is a front end view without illustration of the screw;

FIG. 3 is a right side elevation view thereof, the left side elevation view being a mirror image thereof;

FIG. 4 is a top plan view thereof;

FIG. 5 is a bottom plan view thereof; and,

FIG. 6 is a rear elevational view thereof, undisclosed portions are not part of the claimed design.

The phantom lines in the drawings indicate environmental structure which forms no part of the claimed design.
